COMBINATION BROILER AND TOASTER

William N. Angelus, Alma, Mich.

Application August 3, 1951, Serial No. 16,143

Term of patent 14 years

(Cl. D81—10)

To all whom it may concern:

Be it known that I, William N. Angelus, a citizen of the United States, residing at Alma, in the county of Gratiot, State of Michigan, have invented a new, original, and ornamental Design for a Combination Broiler and Toaster, of which the following is a specification, reference being had to the accompanying drawing, forming a part hereof.

Fig. 1 is a front view in perspective of a combination broiler and toaster embodying my new design; and

Fig. 2 is a rear view thereof.

The side not shown is substantially plain.

I claim:

The ornamental design for a combination broiler and toaster, as shown and described.

WILLIAM N. ANGELUS.
